UNITED STATES PATENT OFFICE

2,263,518

SAFETY WATER LIGHT

William B. Riner, Cincinnati, Ohio

Application July 28, 1939, Serial No. 287,173

3 Claims. (Cl. 177—329)

This invention relates to safety lights and more particularly to a safety light adapted for marine use.

This invention is an improvement over the safety light structures embodied in my prior Patents No. 2,104,762 which issued January 11, 1938 and No. 2,148,323 which issued February 21, 1939.

An object of this invention is to provide a light which may be connected to a life saving ring or belt and which is adapted to be removably mounted in a convenient position on a vessel so that when the life belt ring is removed from its port the safety light which is connected thereto will also be pulled off of the support and will automatically light up so that the position of the life belt or ring in the water can be readily determined in the dark.

Another object of this invention is to provide an improved safety light of this character in combination with an improved holder therefor which is adapted to be mounted on a vessel so that the safety light can be quickly removed from the holder, but is normally held against movement, the holder being of such a character as to eliminate the use of tools to remove the light therefrom.

A further object of this invention is to provide in a light of this character an improved battery holder or clamping means so as to removably hold the battery in the container or outer shell.

A still further object of this invention is to provide an improved circuit closing means which is so constructed that it is normally in a circuit breaking position, but will automatically move to a circuit closing position when the device has been removed from the support and projected into the water.

Embodying the foregoing aims and to others which may hereinafter appear, the invention consists of the novel construction, combination and arrangement of parts as will be more specifically referred to and illustrated in the accompanying drawings, wherein is shown an embodiment of the invention, but it is to be understood that changes, variations and modifications may be resorted to which fall within the scope of the invention as claimed.

In the drawings:

Figure 1 is a detailed side elevation of a safety light according to an embodiment of this invention.

Figure 2 is a sectional view taken on the line 2—2 of Figure 1.

Figure 3 is a sectional view taken on the line 3—3 of Figure 2, and

Figure 4 is a vertical section of a modified form of this invention.

Referring to the drawings and first to Figures 1 to 3 the numeral 10 designates generally a safety light constructed according to an embodiment of this invention. The safety light 10 comprises a cylindrical housing 11 formed with an inner flat bottom 12 provided with a central opening 13, an outer bottom formed of a cup-shaped member 14 having a laterally projecting flange 15 and an upwardly projecting flange 16 integral with the flange 15 encompassing and secured to the lower end of the housing 11. The cup-shaped member 14 on the inside thereof has a weight element 17 secured therein so that when the shell 11 is mounted in the water the weight 17 will maintain the device in an upright position. The inner bottom 12 as shown in the drawings abuts against the adjacent end of the housing 11 and the flange 15 of the outer bottom engages against the outer or lower face of the inner bottom 12.

The upper or opposite end of the housing 11 has a ring 18 mounted therein, the ring 18 having a flange 19 telescoping the upper end of the housing 11 and if desired the flange 19 may be soldered or otherwise firmly secured to the housing 11. A light base member generally designated as 20 is mounted on top of the ring 18 and comprises an outer flange 21 which is adapted to engage the upper surface of the ring 18 and an inner base plate 22 which is upwardly offset as by an extension 23 from the outer flange 21. The plate 22 is provided in substantially the center thereof with an opening 24 the purpose for which will be hereinafter described. The base member 20 is of inverted cup-shape and formed with a lateral extending annular flange at its bottom.

40 The base member 20 is secured to the housing 11 through the ring 18 by means of bolts or screws 25 which are threaded into a clamping ring 26. The clamping ring 26 is positioned on the inner side of the ring 18 and has an inner diameter substantially equal to the inner diameter of the top ring 18. A sealing gasket 27 is interposed between the flange 21 and the top ring 18 so as to prevent any water or moisture from entering the interior of the housing 11. The base plate 22 outwardly from the opening 24 is provided with an upstanding ring or flange 28 and an annular lens 29 engages on the base plate 22 about the flange or ring 28. As gasket 20 is interposed between the lower end of the cylindrical lens 29 and the upper face of the base plate 22.

A cover or hood generally designated as 31 is mounted on top of the lens 29 and comprises a dome-shaped body 32 having an annular flange 33 projecting outwardly and beyond the outer diameter of the lens 29. Clamping bolts 34 engage through openings 35 provided in the flange 33 and these bolts 34 are threaded into the base member 20. The bolts 34 may be locked by means of lock nuts 36 which engage the underside of the flange 33 and are threaded onto the bolts 34. The body 32 at its lower end is provided with an annular downwardly projecting flange 37 about which the upper end of the lens 29 engages and a gasket 38 is interposed between the upper end of the lens 29 and the underside of the flange 33 so as to seal the cover or hood 31 on the lens 29.

The cover or hood 31 is provided with a top wall 39 having an opening 40 axially thereof and a switch structure generally designated as 41 is mounted in the opening 40. The cover or hood 31 is provided with an upwardly projecting neck 42 having exterior threads 43 and a cap 44 is threaded onto the threads 43 and is provided with an opening 45. The switch structure 41 includes a spring-pressed plunger 46 and a threaded stem 47 which engages through the opening 40 and is tightly secured therein by upper and lower nuts 48 and 49 respectively. A flexible diaphragm 50 is interposed between the cap 44 and the outer end of the neck 42 and engages the upper end of the plunger 46. In this manner the switch structure 41 is normally sealed against the entrance of water. The tension of the plunger 46 is such that when the safety light structure has been removed from the holder to be hereinafter described the switch will be biased to a closed or circuit closing position and will normally flex the diaphragm 50 upwardly into the opening 45 in the cap 44.

A battery retainer generally designated as 51 is mounted within the housing 11 and comprises a shell 52 and a plurality of spaced longitudinally extending bars or strips 53 of greater length than and which are secured as by soldering or other fastening means to the outer periphery of the shell 52. The lower ends of the strips or bars 53 are bent right-angularly and outwardly as at 54 providing holding feet which are adapted to be fastened as by soldering or the like to the upper surface of the inner bottom 12. The strips 53 extend above the top of shell 52 and have their upper terminal portions bent in a manner to form what may be termed lateral extensions each formed of a right angularly and outwardly disposed portion 55 and an upwardly disposed portion 56 arranged at right angles to the portion 55. The portions 56 engage the inner surface of the housing 11 and engage beneath the lower edge of an inner ring 57 which is fixedly secured to the inner surface of the housing 11 at a point upwardly from the lower end thereof.

A battery 58 is removably mounted in the shell 52 and is provided with a pair of poles or terminals 59 and 60. In the present instance the battery 58 is substantially square in transverse section and the shell 52 has a similar configuration in transverse section so that the battery 58 may be readily mounted in the shell 52. The battery 58 is releasably held in the retainer 51 by means of a battery clamping bar 61 which extends across the top of the battery 58 with slightly downwardly offset end portions 62 which are adapted to engage a pair of diametrically opposed portions 55 of a pair of extensions. The

bar 61 is removably held in clamping position by means of nuts 63 which engage screws 64 carried by the said pair of apertured diametrically opposed portions 55 of the said pair of extensions. The bar 61 at a point in substantially the longitudinal center thereof and on one edge is provided with a recessed portion 65 to clear terminal 59. The body of housing 10, inner bottom 12, retainer 51, ring 57, clamping bar 61, nuts 63 and screws 64 correlate to form a permanently fixed holder for and having the battery removably mounted therein. The retainer 51 prevents the battery from shifting on the inner bottom 12 and maintains the battery coaxially with the housing 11. The bar 61 in connection with a pair of the extensions of the retainer 51, the nuts 63 and screws 64 removably secures the battery in the retainer 51. The ring 57 prevents the retainer 51, with the battery arranged in the latter from shifting lengthwise of the housing 11.

A lamp socket 66 is mounted within the lens 29 being supported by means of a supporting bar 67 which is secured to the base plate 22 by means of a screw or bolt 68. The socket 66 includes a lower contact strip 69 which is connected to the pole 60 of the battery 58 by means of a wire 70. The socket 66 also includes a second contact strip 71 which has one end of a wire 72 secured thereto. The opposite end of the wire 72 is connected to the switch structure 41. A wire 73 connects the pole 59 with the switch 41 so that upon closing of the switch 41 a circuit will be completed from the pole 59 through the wire 73, switch 41, wire 72, contact strip 71, light bulb 74, contact strip 69, and wire 70 back to the other battery pole 60.

The light structure 10 is adapted to be supported in a convenient position by means of a holder structure generally designated as 75, where it may be attached to a safety belt or buoy (not shown) which is tied to ring 88. This structure 75 includes a vertically disposed base plate 76 which at its lower end is provided with a ring 77 engaging about the cup-shaped member 14 and against the underside of the flange 15. An upwardly extending arm 78 is carried by the ring 77 and may be secured to the vertical bar or base member 76 by suitable fastening devices. A pair of resilient longitudinal arcuate clamping arms 79 are carried by the base member 76 above the lower end thereof and are secured by any fastening means to the base member 76. The clamping arms 79 may be provided with out-turned free end portions 80 to facilitate the positioning of the shell 11 therebetween. A switch-depressing member 81 comprising angularly related bars 82, downwardly extending members 83 and V-shaped cap-engaging members 84 is adapted to engage beneath the lower edge of the cap 44 so as to yieldably hold the depressing member 81 in applied position on the cap 44. The depressing member 81 is provided with a downwardly projecting member 85 which is engageable with the diaphragm 50 in the center thereof so as to depress the plunger 46 and hold this plunger in a normal circuit-breaking position. The switch structure 41 is similar to the switch structure embodied in my prior patents hereinbefore mentioned.

The switch-depressing member 81 has a chain or flexible member 86 secured at one end thereto and the opposite end of the chain or flexible member 86 is secured to an eye or ring 87 which is carried by the base member 76 at a point adjacent the upper end thereof. The housing 11

at a point adjacent the upper end thereof has a ring 88 which is carried by a strap having an arcuate intermediate portion 89 and upper and lower portions 90 which are adapted to be secured as by fastening members 91 to the exterior of the housing 11. The ring 88 is provided for the purpose of securing one end of a chain or other suitable flexible member thereto with the opposite end of this latter chain secured to a life preserver in the form of a ring or other buoyant structure.

In Figure 4, there is disclosed a modified form of this safety light wherein the light structure 10^a is normally in an inverted position from the light structure 10. The light structure 10^a comprises a cylinder 11^a having an inner bottom 12^a provided with a central opening 13^a and an outer bottom 14^a of cup-shaped member provided with an outer flange 15^a and an annular flange or extension 16^a integral with the flange 15^a. A weight 17^a is secured to the inner concave side of the cup-shaped member 14^a. A lower ring 18^a provided with an upwardly extending annular flange 19^a is secured to the upper end of a shell 11^a and a lens base member 20^a similar to the base 20 is secured to the lower ring 18^a by means of bolts 25^a which are threaded into a clamping ring 23^a. A gasket 27^a is interposed between the lens base 20^a and the upper ring 18^a. A lens 29^a of substantially cylindrical construction engages about a rib 28^a carried by the base member 20^a and a dome-shaped hood or top 31^a is secured on the lower end of the cylindrical lens member 29^a by means of holding bolts 34^a. The bolts 34^a engage through a flange 33^a carried by the upper portion of the hood or dome member 31^a and an annular rib 37^a is carried by the hood or some member 31^a and about which the lower end of the lens 29^a engages. The hood 31^a at its lower portion is provided with an annular downwardly projecting flange 42^a, the purpose for which will be hereinafter described.

A battery 58^a similar to the battery 58 is mounted within a retainer 51^a similar to the retainer 51 and a battery clamping bar 61^a is removably mounted on the retainer 51^a by means of thumb nuts 63^a which are threaded on the bolts 64^a engaging through laterally projecting extensions 55^a carried by the longitudinally extending bars or strips 53^a which are fastened to the inner shell 52^a. Ring 57^a is fixed to the inner shell surface of the housing 11^a and downwardly projecting extensions 56^a are carried by the lateral extensions 55^a and engage above the ring 57^a. A lamp socket 66^a is supported in an opening 24^a provided in the base member 20^a by means of a supporting bar 67^a. A contact strip 69^a is carried by the socket 66^a. A light bulb 74^a is removably mounted in the socket 66^a. A liquid switch 41^a is removably secured in a resilient holder 92 which is fixed to a plate 93 fastened to the inner surface of the housing 11^a. One side of the switch 41^a is connected as by a wire 72^a to a battery pole 59^a and a second wire 73^a is connected at one end to the opposite side of the liquid switch 41^a and at the opposite end to the contact strip 69^a. A wire 70^a is connected at one end to a second battery pole 60^a and at the opposite end to the terminal or contact strip 71^a.

With the exception of the switch 41^a and the chain at the top of the hood, the structure of the light 10^a is identical with the light 10 and the slight change in the top of the hood 31^a.

The light member 10^a is supported by means of a supporting member 75^a which comprises a

back or base member 76^a and a cup-shaped lower member 94. The cup-shaped member 94 comprises a bottom wall 95 and an upstanding annular flange or rim 96 which is adapted to engage about the flange or neck 42^a so as to hold the inverted light member 10^a. A horizontally disposed bar or arm 87 is carried by the cup-shaped member 94 and is provided with a vertically disposed arm 98 which is secured to the lower end of the base member 76^a. A resilient clamp 79^a similar to the clamp 79 is secured at its intermediate portion 99 to the outer side of the base 76^a.

In the use and operation of this safety light where the light structure 10 is used, the supporting member 75 is secured to the desired part of the vessel and a life preserver is connected to the ring 88. The bottom of the light structure 10 is adapted to seat in the ring 77 and the clamp 79 will firmly hold the light body in a vertical position on the supporting structure 75. The switch depressing member 81 is snapped over the cap 44 so as to depress the switch plunger 46 and maintain the light circuit 25 to the light bulb 74 in an open position.

In the event it is necessary to use the light 10 the cylinder 11 may be grasped and pulled laterally or forwardly, which movement will release the cup-shaped member 14 from the ring 77 and at the same time, the clamping or holding member 79 will yield to release the cylindrical portion 11 of the light 10. If desired, initially the switch depresser 81 may be first pulled off of the cap 44, but in an emergency it is not necessary to do this as the withdrawal or release of the light 10 from the holder 75 and the outward movement thereof will release the depresser 81 by reason of the fact that the chain or flexible member 86 is connected to one of the clamping members 84 and forcible pulling of the light structure 10 will expand the yieldable clamping members 83, 84. As soon as the depresser 81 is released from the cap 44 the plunger 46 will flex the sealing diaphragm 50 forwardly and the electric circuit to the light bulb 74 will be closed. This circuit will then remain closed until the light structure 10 is replaced on the holder 75 and the depresser 81 is restored to the cap 44. The weight 17 will maintain the light 10 in an upright position in the water.

Where the light structure 10^a is used the light may be released from the holder 75^a by pulling the entire structure outwardly from the upper end thereof so as to release the housing 11^a from the holding clamps 79^a. In this form the inverted upper end 31^a of the light rests on the supporting cap 94 so that when the light structure 10^a is released from the clamp 79^a it may be projected into the water. The weight 17^a will cause the light 10^a to turn over to its upright position with the hood 31^a uppermost. When the light structure 10^a is in its operative position the fluid in the switch 41^a will bridge the contacts connected to the wires 72^a and 73^a thus closing the electric circuit from the battery 58^a to the light bulb 74^a. The circuit closing liquid in the switch 41^a is of such volume that the electric circuit to the bulb will not be readily broken by the bobbing or swinging movement of the light structure 10^a in the water.

A light structure constructed according to this invention will provide a factor of safety in connection with a life preserver so that when the life preserver is thrown into the water at night the exact position of the life preserver can be

readily determined. The battery used with this light structure is of such capacity that the light bulb will be maintained in a lighted condition for a considerable period of time.

What I claim is:

1. A safety water light comprising, in combination a cylindrical housing closed at its top, said housing including an inner bottom section in the form of a flat annulus bearing against the bottom edge thereof and an outer bottom section for closing the bottom of the housing, said outer bottom section formed of an annular angle-shaped outer portion having an outer part encompassing and secured to the body of the housing and an inner part abutting the outer marginal portion of the lower face of said inner section and a cup-shaped inner portion integral with and depending from said inner part and provided with a weighting means.

2. In a safety water light comprising in combination a buoyant cylindrical housing having a chamber at its top, an electric lamp in said chamber and a bottom formed of inner and outer sections, said outer section including a weighing means, a battery within the housing, seated on

said inner bottom section, and connected to the lamp, retaining means for the battery mounted on said inner bottom section, means secured to said retaining means for removably securing the battery in said retaining means, and a holding ring secured to the inner face of said housing and bearing on the said retaining means.

3. In a safety water light an open top buoyant housing, a flat ring seated on the top edge 10 of and formed with a flange encompassing and secured to the upper portion of the housing, a clamping ring positioned against the inner face of said flat ring, a lamp chamber forming structure disposed at the open end of the housing and 15 formed of superimposed sections detachably connected together, the lower one of said sections constituting an inverted axially apertured lamp base formed with an annular flange seated on said flat ring, means for detachably connecting the flange on said lamp base and said rings together, and the upper one of said sections of said structure including means for suspending a switch within the lamp chamber for the lamp.

WILLIAM B. RINER.
